FIG. 1 is a top front perspective view of an end cap for a dryer air system according to my new design.

FIG. 2 is a bottom rear perspective view thereof.

FIG. 3 is a right side view thereof.

FIG. 4 is a front view thereof.

FIG. 5 is a left side view thereof.

FIG. 6 is a rear view thereof.

FIG. 7 is a top view thereof; and,

FIG. 8 is a bottom view thereof.

The broken lines immediately adjacent to the inside wall of the outer pipe and the outside wall of the inner pipe in FIG. 6 represent the boundaries of the claimed design. The broken lines in the Figures illustrate the portions of the design that form no part of the claimed design. None of the broken lines form any part of the claimed design.
